THOMAS B. SHANAHAN, OF ROCHESTER, NEW YORK, ASSIGNOR TO LEGAL LEVEL
LIGHT CO., OF ROCHESTER, NEW YORK, A CORPORATION OF NEW YORK.

NON-GLARE HEADLIGHT.

1,354,699.

Specification of Letters Patent.

Patented Oct. 5, 1920.

Application filed January 7, 1918. Serial No. 210,594.

To all whom it may concern:

Be it known that I, THOMAS B. SHANAHAN, a citizen of the United States, and a resident of Rochester, in the county of Monroe and State of New York, have invented a certain new and useful Non-Glare Headlight, of which the following is a specification.

This invention has for its object a non-glare reflector for the headlights of motor cars which is particularly simple and economical in construction and highly efficient in use; and the invention consists in the novel features and in the combinations and constructions hereinafter set forth and claimed.

In describing this invention, reference is had to the accompanying drawings in which like characters designate corresponding parts in all of the views.

Figure 1 is a vertical sectional view of a headlight embodying my invention; and Fig. 2 is a face view of the reflector.

1 designates the headlight, and 2, the concave or parabolic reflector thereof, the reflector having a passage 3 at its rear end in axial alignment with its focal axis, for supporting a lamp socket 4 which receives the plug of the incandescent electric lamp 5.

6 is a supplemental reflector forming part of the main reflector 2 and located at the central portion or zone of the major surface of the reflector at one side of the focal axis and within the curve of the major surface 35 of the reflector 2, the supplemental surface 6 being usually located below such focal axis so as to project forwardly, in a shaft of parallel rays, rays that would otherwise strike the lower central portion of the main or 40 major surface and be diffused thereby. It will be understood that the glare from headlights is due to the rays projected from the central zone or portion of the reflector. The rays of light passing upwardly to the upper 45 portion of the reflector are thrown downwardly and hence do not strike the eyes of pedestrians or of the drivers of approaching cars.

The non-glare surface 6 is spherically curved, and as here shown it is substantially a quarter of a sphere and shields or en-

circles the rear lower quarter of the bulb of the incandescent electric lamp. The surface is located within the curve of the remainder of the reflector and said remainder is located throughout its extent in said curve and the portion adjacent the front end of the auxiliary reflector meets such front edge instead of extending under and behind it.

Heretofore, pockets in which the electric bulbs have been located have been depressed or located in the rear of the curve of the main or major surface of the reflector.

In my headlight, owing to the location of the non-glare surface 6 and to the curvature thereof, the rays of light which ordinarily would strike the lower central portion of the reflector are projected forwardly in a horizontal shaft of substantially parallel rays which are too low down to strike the eyes of 70 pedestrians or the drivers of approaching cars within striking distance of the car provided with my headlight; and the light that in ordinary headlights blinds the pedestrians or the drivers of approaching cars, is 75 projected by the surface 6 forwardly in a line below the eyes of pedestrians or drivers and lights the road farther ahead than headlights unprovided with the surface 6.

The rays of light from the non-glare surface 6 strike the eyes of a pedestrian or of the driver of an approaching car, if at all, only when he is too far in front of the car to be in danger of being struck by the car.

What I claim is:

A concave reflector having a portion of its wall at one side and adjacent to its focal axis projected into the reflector, said portion being formed with a depressed auxiliary reflecting surface adjacent the focal axis and 90 located within the curve of the reflector; the remainder of the reflector being located in said curve and the portion of the reflector near the front edge of the auxiliary reflecting surface meeting said front edge, substantially as and for the purpose described.

In testimony whereof I have hereunto signed my name at Syracuse, in the county of Onondaga and State of New York, this 5th day of December, 1917.

THOMAS B. SHANAHAN.
